UNITED STATES PATENT OFFICE

JOHN R. BOYD, OF PITTSBURGH, PENNSYLVANIA, ASSIGNOR TO ROBERT L. WICKLINE,
OF PITTSBURGH, PENNSYLVANIA

FIRE EXTINGUISHER

Application filed July 17, 1929. Serial No. 378,939.

My invention relates to certain new and useful improvements in fire extinguishers employing carbon tetra-chloride solution as a fire damping medium, and somewhat of 5 the type disclosed in my United States Patent No. 1,671,398.

The fire extinguisher disclosed in the above mentioned patent has proven unsuccessful, owing to the fact that the invention 10 involved lacks several very important features imperative to the successful operation of a device of this kind.

It is well known that air under pressure will condense moisture, and the presence of 15 the latter is not only detrimental to the container but deteriorates the carbon tetra-chloride, and thereby diminishes its efficiency as a fire extinguishing agent. Further, as carbon tetra-chloride is very sus- 20 ceptible to evaporation and expansion due to temperature changes, and as it is essential to maintain the carbon tetra-chloride under normal atmospheric pressure, it has been found necessary to provide means for 25 preventing the evaporation of the carbon tetra-chloride solution and for permitting of its expansion within its container.

Important objects of the present invention are to provide a fire extinguisher of 30 the character described which is highly efficient in extinguishing fires of any nature, which embodies novel means for expelling all moisture from the air compression tank, which functions automatically for main- 35 taining the carbon tetra-chloride solution under normal atmospheric pressure while preventing the evaporation of said solution, which is simple in its construction and ar- 40 rangement, compact, durable and efficient to use, and comparatively inexpensive 45 to manufacture and operate.

With the foregoing and other objects in view which will appear as the description 50 proceeds, the invention resides in the combination and arrangement of parts and in the details of construction hereinafter described and claimed, it being understood that changes in the precise embodiment of the invention hereinafter disclosed can be 55 made within the scope of what is claimed.

without departing from the spirit of the invention.

In the drawings wherein like numerals of reference designate corresponding parts throughout the several views:

55

Figure 1 is a top plan view of a fire extinguisher constructed in accordance with the invention.

Figure 2 is a fragmentary side view of the device with the upper end thereof shown in cross section.

Figure 3 is a side view of the device with the lower end thereof shown in cross section.

Referring in detail to the drawings 1 denotes a cylindrical, vertically disposed tank, having a closed bottom 2, and provided for storing the carbon tetra-chloride solution 3. A cylindrical, vertically disposed, compressed air tank 4, provided with a closed bottom 5, is mounted in the solution tank 1. The air tank bottom 5 is rounded and rests upon the solution tank bottom 2. The relative capacities of the tanks 1 and 4 are preferably uniform, although the same may 75 be varied to meet conditions found in practice.

A closure head 6 covers the upper open ends of the tanks 1 and 4, and is preferably fixed to the latter by welding, or in any 80 other suitable manner to hermetically seal the tanks 1 and 4. The air tank 4 is supported by the closure head 6 and surrounded by the carbon tetra-chloride solution 2 in the tank 1.

A charging valve 7, blow-off valve 8, a control valve 9, and a relief valve 10, are all suitably and detachably mounted on the closure head 6. The charging valve 7 communicates with the air tank 4, and a conduit 11 establishes communication between the charging valve 7 and the solution tank 1.

The blow-off valve 8 communicates with the air tank 4 and carries a vertically disposed tube 12. The open lower end 13 of 95 the latter is disposed in close proximity to the bottom 5 of the air tank 4. The blow-off valve 8 is provided with a connecting sleeve 14 which is adapted for connection with an air supply hose for supplying the 100

necessary compressed air to the air tank 4 through the tube 12.

The control valve 9 communicates with the solution tank 1 and carries a vertically disposed tube 15. The open lower end 16 of the latter is disposed adjacent to the bottom 2 of the solution tank 1. The control valve 9 is provided with a connecting sleeve 17 for the attachment of the hose 18. The latter carries a nozzle 19 and is adapted for playing the carbon tetra-chloride solution 3 upon the fire to be suppressed. The tubes 12 and 15 are provided to permit of conveniently mounting respective associated valves 8 and 9 upon the top of the closure head 6 as the air pressure is above any other fluids in tanks 1 and 4.

The relief valve 10 communicates with the solution tank 1. The relief valve 10 is formed with a rightangularly extending passage 20, the inner end of which communicates with a valve chamber 21. The relief valve 10 includes a needle valve member 22 for opening and closing the passage 20. A ball valve member 23 is loosely mounted in the chamber 21 and seats in a valve plug 24, which is detachably and adjustably connected to the lower end of the relief valve 10. The valve plug 24 is formed with a vertically extending passage 25 which establishes communication between the solution tank 1 and the valve chamber 21.

A pair of pressure gauges 26 and 27 are mounted on the closure head 6, and communicate with respective tanks 1 and 4 for registering the pressures of the fluids within the latter. The closure head 6 is further provided with a plug 28 for supplying the solution to the tank 1 or for draining the solution therefrom.

In practice the operation of my improved fire extinguisher is as follows:—The carbon tetra-chloride solution 3 is poured into the tank 1 through the opening for the plug 28 and the latter replaced in position. The blow-off valve 8 is opened, and air is forced into the air tank 4, through the connecting sleeve 14, blow-off valve 8, and the tube 12, until the desired air pressure is registered on the pressure gauge 27, after which the blow-off valve 8 is closed.

While charging valve 7 is closed, the compressed air within the air tank 4 cannot charge the solution 3 in the tank 1. Except when the device is in actual use, the solution 3 is maintained at normal atmospheric pressure within the tank 1. When the extinguisher is stored for future use or emergencies, the needle valve member 22 is slightly released to partially open the passage 20. Upon expansion of the solution 3, due to temperature changes, the excess air and solution, within the tank 1, will automatically actuate the ball valve member 23, and escape through the valve plug passage 25,

valve chamber 21, and the passage 20, thereby eliminating the possibilities of explosion due to such expansion. After the expulsion of such excess air and solution, the ball valve member 23 will automatically re-seat itself by gravity in the valve plug 24, thereby closing the passage 25 and again sealing the tank 1 to prevent loss of the solution 3 by evaporation.

When the extinguisher has been stored for some time, the compressed air within the tank 4 will condense moisture, which will accumulate upon the air tank bottom 5. As moisture will deteriorate the carbon tetra-chloride solution, any such accumulated moisture is first blown from air tank 4, through the tube 12 and connecting sleeve 14, by momentarily releasing the blow-off valve 8 just prior to operating the device.

In operating the device for extinguishing a fire, the moisture is first expelled from the tank 4, as above stated, and the relief valve 10 is closed. The charging valve 7 is now opened admitting the compressed air from the tank 4 to the tank 1 and charging the solution 3 in the latter. The control valve 9 is regulated to provide the desired stream of solution, which is forced through the tube 15, hose 18, and nozzle 19.

In discontinuing the use of the extinguisher after only a portion of the compressed air and the solution have been used, the control valve 9 and the charging valve 7 are closed, and the relief valve 10, is again partially opened to release and dissipate the air pressure from the solution tank 1. The device is now again ready for storing and re-use when required.

The present invention provides a highly efficient fire extinguisher which functions perfectly in every respect, and which is particularly essential in rural districts lacking fire fighting facilities.

What I claim is:

1. In combination, a fire extinguisher for using carbon tetra-chloride solution comprising a solution tank, a compressed air tank, valve-controlled means establishing communication between said tanks, means for regulating the discharge from said solution tank, and means for automatically maintaining atmospheric pressure in said solution tank, said last mentioned means further preventing the entrance of air therethrough to said solution tank.

2. In combination, a fire extinguisher for using carbon tetra-chloride solution comprising a solution tank, a compressed air tank, valve-controlled means establishing communication between said tanks, means for regulating the discharge from said solution tank, and means for automatically maintaining atmospheric pressure in said solution tank and further for normally pre-

venting the escape of the evaporation of said solution in the latter.

3. In combination, a fire extinguisher of the character described for using carbon tetra-chloride solution comprising a solution tank, a compressed air tank mounted within said solution tank, a closure head covering the tops of said tanks, valve-controlled means establishing communication between said tanks, a control valve mounted on said closure head for regulating the discharge from said solution tank, a tubular member communicating with said control valve and having an open lower end disposed adjacent to the bottom of said solution tank, a blow-off valve mounted on said closure head for expelling moisture from said compressed air tank, and a tubular member communicating with said blow-off valve and having an open lower end disposed adjacent to the bottom of said solution tank.

4. In combination, a fire extinguisher of the character described for using carbon tetra-chloride solution comprising a solution tank, a compressed air tank mounted within said solution tank, a closure head covering the tops of said tanks, valve-controlled means establishing communication between said tanks, a control valve mounted on said closure head for regulating the discharge from said solution tank, a tubular member communicating with said control valve and having an open lower end disposed adjacent to the bottom of said solution tank, a blow-off valve mounted on said closure head for expelling moisture from said compressed air tank, a tubular member communicating with said blow-off valve and having an open lower end disposed adjacent to the bottom of said solution tank, and an automatically operating valve element for maintaining atmospheric pressure in said solution tank and further for normally preventing the escape of the evaporation of said solution in the latter.

15 In testimony whereof I affix my signature.
JOHN R. BOYD.
